Application September 27, 1935, Serial No. 42,381

6 Claims. (Cl. 116—138)

This invention relates to a structurally and functionally improved warning signal, capable of use in numerous different associations, but primarily intended to be employed as a signal for use on vehicles as well as for the purposes of a fog signal, a burglar alarm, and many other uses.

By means of the present invention, there is furnished a warning signal which, in operation, will produce a note or tone having extreme carrying power without, however, such tone being raucous or objectionable. In fact, a structure embodying the present invention will be of such a nature that it may, without detriment to carrying power, be of a somewhat musical nature.

A further object of the invention is that of constructing a warning signal, the parts of which are equally adapted for operation by pressure or vacuum; it being only necessary, in certain instances, to make a slight adjustment of the parts to assure proper operation under either source of power.

An additional object is that of furnishing an apparatus of this nature which will embody relatively few parts, each individually simple and rugged in construction and which parts may be largely manufactured by automatic or semi-automatic machinery and subsequently assembled with minimum effort to furnish a unitary signaling apparatus operating with freedom from difficulties over long periods of time.

With these and other objects in mind, reference is had to the attached sheet of drawing illustrating one practical embodiment of the invention, and in which—

Fig. 1 is a fragmentary sectional side view of the unit;

Fig. 2 is a rear view thereof, with certain of the parts broken away to disclose the underlying construction; and

Fig. 3 is a sectional view taken along the lines 3—3 and in the direction of the arrows as indicated in Fig. 1.

In these views, the numeral 5 indicates a trumpet or sound propagator which may conveniently form a part of the apparatus and which can be attached to the casing 6 by employing, for example, an exteriorly and interiorly threaded bushing 7, the threads of which engage corresponding threads formed adjacent the inner end of the trumpet and the inner surface of the casing collar 8. The rear face of the casing 6 may be closed by a housing 9, these parts being connected in any suitable manner, as for example by means of bolts and nuts 10. For the

purpose of obtaining access to the interior of the casing, the member 9 may be formed with a rearward opening normally covered by a cap 11, which may be provided with a vent 12 through which air may flow.

As shown especially in Fig. 1, the casing 6 has a central and forwardly extending opening, and to the rear of this opening is formed a passage 13, to which a nipple 14 may be extended, to be connected to a conduit (not shown), supplying fluid under pressure, or coupled to a source of vacuum.

Clamped between the peripheral portions of sections of the housing 9 and the casing 6 is a diaphragm which has its central area free to vibrate within the space defined by the casing portion. This diaphragm is preferably perforated at its center to accommodate the screw threaded stem 16 of a valve 17. This valve has its body movably mounted within the opening of the casing 6 with its edges slidably engaging the walls defining such opening. While the parts should fit in such manner that the valve obstructs the opening, they should not engage each other in a manner such that there would be danger of binding or of too great a frictional contact between these parts. A modulator 19 is secured to the diaphragm 15 in any suitable manner. This modulator has a central screw-threaded aperture in line with the perforation of the diaphragm. Extending through this aperture is the stem 16, and the latter is held in place by means of a lock nut 18. In the latter connection, it will be understood that, due to the area and mass of the member 19, as well as the fact that it extends within the area through which fluid rushes, it will serve to diminish the frequency of vibration of the diaphragm 15 and parts associated therewith.

With the parts assembled as shown, it will be apparent that the nipple 14 may be connected to a source of vacuum or a source of fluid under pressure. According to the source of power, the position of the valve is adjusted. Such adjustment may be effected by simply removing the cap 11 and thereafter by turning the stem 16, shifting the latter, together with the valve, in a direction parallel to the axis of the collar 8.

If, for example, vacuum is employed, it will be apparent that the area of the diaphragm 15, as compared to the area of the valve 17, is so great that the diaphragm will be flexed towards the collar 8, thus shifting the valve to a position at which air may rush through the collar and the opening of the housing 6 towards the outlet 13. 55

This, of course, will result in a breaking of the vacuum, and incident to the resiliency of the diaphragm 15 the parts will return to their initial position. This operation will be repeated so rapidly that vibration at acoustical frequencies will follow. Consequently, and with proper adjustment, a tone embodying the desired characteristics will be produced. If the valve is adjusted so that pressure may be used to actuate the apparatus, it is apparent that fluid under pressure entering through the passage 13, will cause the diaphragm to be flexed rearwardly until the valve 17 has been drawn into the casing 6 to a position at which the fluid under pressure may escape between the edge of the valve and the housing. Incident to such escape, the pressure within the casing will be relieved, and the diaphragm will return to its normal position. These operations will be repeated at such a rate that there will again be present vibrations at acoustical frequencies.

Under all conditions of operation, it will be apparent that surges set up in the rear part of the housing and incident to diaphragm vibration will not set up a condition of vacuum or pressure because this will be relieved through the vent 12. Also, it is to be observed that one of the main features of the present invention is that of guarding against the possibility of binding between the casing and the valve and irrespective of the amplitude of vibration to which the diaphragm is subjected and the consequent tendency to oscillate on the part of the stem 16. One method of overcoming any binding tendency is that especially shown in the drawing, in which it will be observed that a suitable number of guiding elements 20 extend rearwardly from the face of the valve in line with the edge of the latter so that they lie closely adjacent to the edge defining the central opening of casing 6. Thus, even if the valve body is moved to a position where it extends slightly beyond the casing material, these guide elements will still maintain the valve in proper condition (i. e., confine its movements to straight reciprocation). Consequently, any tendency of the parts to bind will be entirely overcome.

Thus, among others, the several objects of the invention as specifically aforesaid are achieved. It will be understood that numerous changes in construction and rearrangement of the parts might be resorted to without in any sense departing from the spirit of the invention as defined by the claims.

Having thus described the invention, what is claimed is:

1. A signaling apparatus including, in combination, a housing formed with a pair of openings, a diaphragm mounted by said housing, a valve connected to said diaphragm and extending adjacent and in sliding contact with the walls defining one of said openings, the other of said openings being intended for connection to a source of fluid having a pressure different from that existing in such housing, and means for confining the movements of said valve to a straight path.

2. A signaling apparatus including, in combination, a housing formed with a pair of openings, a diaphragm mounted by said housing, a valve connected to said diaphragm and extending adjacent one of said openings, the other of said openings being intended for connection to a source of fluid having a pressure different from that existing in such housing, and means extending from said valve and in sliding contact with the walls defining said first named casing opening for guiding the movements of said valve. 5

3. A signaling apparatus including, in combination, a housing formed with a pair of openings, a diaphragm mounted by said housing, a valve connected to said diaphragm and extending adjacent one of said openings, the other of said openings being intended for connection to a source of fluid having a pressure different from that existing in such housing, and guiding elements extending from one of the faces of said valve body 20 and in sliding contact with and parallel to the edges of the casing opening for guiding said valve. 15

4. A signaling apparatus including, in combination, a housing formed with a pair of openings, a diaphragm disposed within said housing, a valve connected to said diaphragm and extending adjacent one of said openings, the other of said openings being intended for connection to a source of fluid having a pressure different from that existing in such housing, and a plurality of 30 guiding elements extending rearwardly from said valve and in sliding contact with the edge of the casing opening to guide said valve, said elements having an outer surface conforming to the operative edge of the valve. 35

5. A signaling apparatus including, in combination, a housing formed with a pair of openings, a diaphragm mounted by said housing, a valve connected to said diaphragm and extending adjacent one of said openings, the other of said openings being intended for connection to a source of fluid having a pressure different from that existing in such housing, guiding elements extending from one of the faces of said valve body 40 and adjacent and parallel to the edges of the 45 casing opening for slidably contacting the same to guide said valve, and means carried by said valve and connected to said diaphragm for adjustably locating said valve and the guiding elements thereof longitudinally with respect to 50 edges of said casing opening.

6. A signaling apparatus including a housing formed with an inlet and an outlet opening, a diaphragm mounted by said housing and to the rear of said openings, a valve mounted for movement within said inlet opening and slidably engaging the walls defining the same, a stem securing said valve to said diaphragm, and said outlet opening being adapted for connection to 60 a source of suction under the influence of which said diaphragm will flex to move said valve to a point at which its body will shift beyond the end of said inlet opening and permit air to flow through said inlet opening to said outlet opening. 65
